UNITED STATES PATENT OFFICE.

JOHN A. KAISER, OF DETROIT, MICHIGAN.

DETACHABLE RUBBER HEEL.

1,270,523.

Specification of Letters Patent. Patented June 25, 1918.

Application filed December 13, 1917. Serial No. 206,890.

To all whom it may concern:

Be it known that I, JOHN A. KAISER, a citizen of the United States of America, residing at Detroit, in the county of Wayne 5 and State of Michigan, have invented certain new and useful Improvements in Detachable Rubber Heels, of which the following is a specification, reference being had therein to the accompanying drawings.

0 This invention relates to a detachable rubber heel and has special reference to means for detachably connecting a heel to a shoe or other footwear so that the heel may be removed when worn or injured and a new heel 15 substituted therefor, without necessarily obtaining the services of a shoemaker or repair man.

The primary object of my invention is to furnish a shoe or other footwear with a fixed 20 plate or member in engagement with which a rubber heel may be easily and quickly placed to be firmly held so that the heel may be used as though permanently or fixedly attached to the shoe.

25 Another object of this invention is to provide a heel fastening means for a shoe wherein the resiliency of the heel contributes toward holding the heel or its fastening means in a useful position relatively to a shoe, thus 30 preventing the heel from becoming accidentally displaced while forming part of a shoe.

A further object of my invention is to provide heel fastening means consisting of comparatively few parts that may be easily manipulated when installing or providing a shoe with a heel in accordance with my invention, and the above and other objects are attained by a mechanical construction that 40 will be hereinafter specifically described and then claimed.

In the drawing,

Figure 1 is a side elevation of a portion of a shoe, partly broken away and partly 45 in section, showing a rubber heel attached thereto;

Fig. 2 is a plan of the heel plate showing the flange thereof;

Fig. 3 is a longitudinal sectional view of 50 a modified form of heel;

Fig. 4 is a longitudinal sectional view illustrating a modified form of fastening means for the heel;

Fig. 5 is a plan of one of the heel plates 55 shown in Fig. 4.

In the drawings, the reference numeral 1

denotes a portion of a shoe devoid of the usual heel and the rear end of the shoe sole 2, which is generally made of leather, has attached thereto, by nails 3 or other fastening means a heel plate 4. The heel plate 4 is made of metal and in plan conforms to the outline of a heel, said heel plate having the forward edge thereof provided with a depending transverse flange 5. The heel plate 65 is also provided with a plurality of key-hole shaped openings 6 and these openings are adapted to register with the recesses 7 in the lower face of the shoe sole 2.

The reference numeral 8 denotes a heel, 70 preferably made of rubber and molded in said heel are nuts 9 or other anchoring means for screws or headed studs 10 protruding from the upper face of the heel 8 and adapted to extend through the openings 6 and 75 have the heads thereof engage the upper face of the heel plate 4. The plurality of screws or studs 10 can be easily and quickly placed in engagement with the heel plate 4, but the studs cannot be shifted into or seated in the 80 narrow portions of the openings without compressing the forward edge of the heel 8. In other words the forward edge of the heel 8 will not engage behind the flange 5 unless the forward edge of the rubber heel is compressed and seated behind the flange. Then 85 the resiliency of the rubber heel will tend to hold the studs 10 in the narrow portions of the openings 6, thus preventing a heel from becoming accidentally displaced relatively 90 to its heel plate. This is a characteristic of my invention, as I am unaware of any rubber heel that is detachable and may be permanently anchored relatively to a shoe sole by having a portion thereof compressed, so 95 that the resiliency of the compressed portion of the heel will always tend to hold the fastening means locked against accidental displacement.

In lieu of holding the rubber heel 8 about 100 the nut 9 or the inner end of the screw or stud 10, the heel 11, as shown in Fig. 3 may be provided with an opening 12 and the nut and screw forced into said opening to be held by the retractile force of the rubber 105 about the nut and screw.

In the modification shown in Figs. 4 and 5, a shoe sole 13 has a recess 14 and a metallic plate 15 that may be connected to the sole by suitable fastening means, as nails 16. 110 The sole plate 15 has a plurality of slots 17 and these slots are adapted to receive tongues

18 of C shaped members 19 mounted in a heel 20 that has an edge thereof engaging the flange 5 of the plate 15.

By having the heels detachable, I may 5 have leather or other kinds of heels to be worn with overshoes or for other purposes, and the heels of a pair of shoes may be changed from one shoe to the other, so that side edges of the heels may be evenly worn.

10 It is thought that the utility of my invention will be apparent without further description, and while in the drawing there are illustrated the preferred embodiments of my invention, it is to be understood that the 15 structural elements are susceptible to such variations and modifications as fall within the scope of the appended claims.

What I claim is:—

1. The combination of a heel plate having 20 a depending flange the entire width thereof, a rubber heel adapted to have the edge thereof sprung into engagement with the flange of said heel plate, and fastening means for attaching said heel to the plate and adapted

to be held in a locked position by the sprung 25 edge of said heel.

2. The combination of a shoe sole, a heel plate attached thereto, and a heel suitably connected to said heel plate and adapted to have its connecting means held against displacement by an entire upper front edge of said heel.

3. The combination with a shoe sole, of a heel plate attached thereto and provided with a depending flange the entire width 35 thereof, a heel, and fastening means detachably holding said heel in engagement with said heel plate, said fastening means being held locked by the resiliency of the upper front edge of said heel against the flange of said heel plate.

In testimony whereof I affix my signature in the presence of two witnesses.

JOHN A. KAISER.
